UNITED STATES PATENT OFFICE.

WILLIAM V. ROBINSON, OF DETROIT, MICHIGAN, ASSIGNOR TO THE ART STOVE COMPANY, OF DETROIT, MICHIGAN, A CORPORATION OF MICHIGAN.

STOVE.

SPECIFICATION forming part of Letters Patent No. 710,616, dated October 7, 1902.

Application filed January 28, 1901. Serial No. 45,089. (No model.)

To all whom it may concern:

Be it known that I, WILLIAM V. ROBINSON, a subject of the King of Great Britain, residing at Detroit, in the county of Wayne and 5 State of Michigan, have invented certain new and useful Improvements in Stoves, of which the following is a specification, reference being had therein to the accompanying drawings.

10 The invention relates to that class of stoves which are formed of sheets of steel and are commonly known as "steel" ranges.

15 The invention consists in the peculiar construction of a hot shelf; further, in its peculiar arrangement in relation to the stove-body, whereby it may be used for heating a water-tank at the end of said body; further, in the peculiar construction whereby said shelf may be readily detached from the stove when 20 not needed.

The invention further consists in the peculiar construction, arrangement, and combination of parts, as hereinafter described and claimed.

25 In the drawings, Figure 1 is a perspective view of a stove to which my improvement is applied, also showing the water-tank detached therefrom. Fig. 2 is a longitudinal section with the water-tank in position for heating.

30 Fig. 3 is a horizontal section illustrating the arrangement of flues. Fig. 4 is a section showing a portion of Fig. 2 with the shelf removed and flue-apertures covered. Fig. 5 is a perspective view of the detachable plate.

35 A is a steel range of any suitable construction, and B is the rear wall thereof.

C is an oven-casing. D is a flue extending above the top, down the side, and below said oven-casing, and E is a return-flue separated 40 from the flue D by the central division-strip F, the arrangement thus far described being the usual construction in stoves of this type.

Heretofore steel ranges have been provided with water-tanks which are suspended from 45 a shelf or extension of the top and have one side bearing against the rear sheet of the stove-casing. As the heated products pass through the flues D and E and come in contact with the rear wall, a certain degree of heat 50 will be imparted to the water in the tank. It

has been found in practice, however, that the water cannot be heated to any considerable extent in this way, and also that to heat it to any appreciable degree time is required.

It is one of the objects of my invention to 55 provide means for quickly heating the water in the tank to any degree desired up to the boiling-point, and, further, to provide a hot shelf or extension which when the tank is removed may be used for other purposes. 60

As shown in the drawings, my improvement comprises the hollow casing G, extending from the rear wall of the stove-casing and in the position where its top plate a will bear against the bottom of the water-tank. This 65 casing is removably attached to the stove-body by providing the latter with the frame b, surrounding flue-apertures c and d, which respectively connect with the flues D and E. The frame b is provided with the hooked 70 flanges e, with which flanges f on the casing G are adapted to engage, as shown in Fig. 3. The flanges e and f are slightly inclined from the perpendicular, so as to form a wedge engagement with each other, which holds the 75 casing G in the position to communicate with the flues c and d. The casing G is provided with a division-strip h, which bears against and forms an extension of the division-strip F, and upon one side of this division-strip is arranged a damper i, adapted to be turned 80 either to close the aperture c or to extend across the flue D.

H is a water-tank provided with the top rim I, which has the hooks J for engaging with 85 sockets in the stove-top.

The parts being constructed as shown and described, it will be understood that when the shelf-casing G is attached to the stove-body and the damper is turned in the position 90 shown in Fig. 3 the heated products will be deflected from their course downward through the flue D and pass into the hollow shelf G and around the partition h therein, returning through the aperture d and flue E. This will 95 cause the top a of the casing G to become heated, which when the tank is in position will impart its heat through the bottom of said tank to the water contained therein. Whenever the oven of the stove is in use, the damper 100

per *i* may be turned into the position shown in Fig. 2, which will close the aperture *c* and open the flue *D*, thereby allowing the products to pass beneath the oven-casing, and thus 5 return through the flue *E*.

The tank *H* may be readily removed at any time when not needed, and this will permit of the shelf *G* being employed as an auxiliary heater. When neither tank or shelf are needed, the latter may be easily detached from the casing, and the flue-openings *c* and *d* can be covered by the detachable plate *K*, as shown in Fig. 4.

What I claim as my invention is—

15 1. The combination with a stove having a sheet-metal vertical end wall and separated downgoing and return flues formed in adjacency thereto, of a hollow shelf detachably connected to project laterally from said end 20 wall and apertured to communicate with said flues, a division - strip in said hollow shelf

matching with the division between said flues and a damper pivotally connected to said shelf and extending on one side of said division-strip.

25

2. The combination of the back wall of the stove forming the outer wall, of up and down going smoke - flues, a transverse aperture through the back wall below the top, extending across both flues, a hollow shelf detachably connected to said back wall, fitting around the aperture, a flat apertured top therefor, a damper carried by the shelf, adapted to close the opening from one flue into the shelf, and a detachable water-tank adapted 30 to rest upon the top of said shelf.

30

In testimony whereof I affix my signature in presence of two witnesses.

WILLIAM V. ROBINSON.
